COMBINED TRASH RECEPTACLES AND CART THEREFOR

Harold Ray Mockler, 4803 E. Hayhurst,
Tucson, Ariz. 85712

Filed Nov. 20, 1972, Ser. No. 307,995

Term of patent 14 years

Int. Cl. D7—07
U.S. Cl. D7—191

fig. 1

fig. 2

fig. 3

fig. 4

FIG. 1 is a perspective view of the combined trash receptacles and cart therefor showing my new design, with the lid of the rear receptacle being removed and the rear receptacle being elevated from the bottom of the cart;

FIG. 2 is a top plan view;

FIG. 3 is a side elevational view; and

FIG. 4 is a front elevational view thereof.

I claim:

The ornamental design for the combined trash receptacles and cart therefor, as shown and described.
